CLAIR L. FARRAND, OF FOREST HILLS, NEW YORK, AND ERNEST ROSS, OF EAST ORANGE, AND PAUL F. GODLEY, OF UPPER MONTCLAIR, NEW JERSEY; SAID GODLEY AND SAID ROSS ASSIGNEES TO FARRAND MFG. CO. INC., OF LONG ISLAND CITY, NEW YORK, A CORPORATION OF NEW JERSEY.

LOUD-SPEAKER.

Application filed November 5, 1926. Serial No. 146,347.

This invention relates to loud speakers and particularly to loud speakers of the cone type.

A well-known type of loud speaker has a diaphragm structure which comprises a cone 5 and a cone frustum positioned with their bases toward each other and cemented together at their outer edges. Loud speakers of this kind are known as "double cone" speakers. One of the problems presented in 10 the manufacture of double cone speakers is to produce an efficient and neat joint between the cone and the cone frustum. In the commercial manufacture of loud speakers this joint should be of such a character that 15 it can be readily and quickly produced without sacrificing the efficiency and neatness of the joint. It is one object of this invention to provide an improved joint between the cone and the cone frustum in a loud speaker 20 of the double cone type which may be quickly and readily produced in the commercial manufacture of the loud speaker and which will be efficient and neat in appearance. It is a further object of the invention to provide 25 an improved joint between the edge of any diaphragm and a supporting member or the like located at the back of the diaphragm, regardless of the exact construction of the diaphragm and regardless of the exactly construction of said member.

The accompanying drawings illustrate the invention as applied to a loud speaker of the so-called "double cone" type, but as herein-after pointed out the improved joint may be 35 utilized in a loud speaker whose construction is quite different from that disclosed in the drawings.

In the drawings:

Fig. 1 is a front elevation of a loud speaker 40 embodying the invention;

Fig. 2 is a side elevation of the speaker shown in Fig. 1; and

Fig. 3 is an enlarged vertical section through the joint between the cone and the cone frustum.

The loud speaker shown in the drawings comprises a conical diaphragm 1 and a cone frustum 2 both made of fibrous material such as paper. The cone and cone frustum 2 are 50 positioned with their bases toward each other

and are joined together by the particular type of joint forming the subject matter of the present invention.

The remaining structure of the loud speaker itself is not important so far as an understanding of the present invention is concerned, but it might be stated briefly that the remaining parts comprise a ring structure 3 in which the edge of the cone frustum 2 is clamped, a base 4 and supporting rods 5 for supporting the ring structure on the base. These rods are secured to the ring structure at 6 and are housed within the cone structure. They pass downwardly through an opening 7 in the lowermost portion of the cone structure and are secured to the base at their lowermost ends. The rods 5 also serve to support the electromagnetic actuating mechanism 8 having an actuating rod 9 connected to the apex of the cone 1 to 70 vibrate it in the well known manner.

The improved joint between the cone 1 and the cone frustum 2 is formed as follows: The cone 1 is provided with a peripheral portion 10 which is bent or flared outwardly and the cone frustum 2 is provided with a corresponding peripheral portion 11 which is bent or flared in the opposite direction. When the cone 1 and cone frustum 2 are positioned with their bases toward each other the outward- 30ly bent portions 10 and 11 form between them a peripheral groove or recess. Within this recess is positioned an ornamental cord 12 which is held in place by a fillet of adhesive which also serves to cement the cone to the cone frustum. The best results have been obtained in practice by bending the portions 10 and 11 to such an extent that they form 35 between them an angle of approximately 90°.

In the commercial production of loud speakers of the type described above the cone frustum 2, either with or without the ring structure secured to it, and the cone 1 are held in two parts of a suitable machine which are made to approach each other until the edges of the cone and cone frustum meet. The parts of the machine are then rotated to cause the cone and cone frustum to make one complete rotation in unison. During this rotation a stream of adhesive is fed to the 100

groove or recess between the peripheral portions 10 and 11. The cord 12 is also applied to the recess during the rotation of the cone and cone frustum by positioning one end 5 of the cord in the recess where it will be gripped by the adhesive and then causing the cord to wind into the groove as the diaphragm structure rotates. The entire structure is then allowed to stand until the adhesive sets 10 and binds the parts together, or if desired, heat may be applied to the joint to set the adhesive more quickly.

The fillet of adhesive 13 not only serves to secure the cone 1 to the cone frustum 2, 15 but it also serves to cement the cord 12 in place. In fact all three parts, namely the cone, the cone frustum and the cord are all bonded together into a unit by the fillet of adhesive so that the cord really plays an im- 20 portant part in attaching the cone to the cone frustum.

The cord 12 conceals the joint between the cone and the cone frustum and greatly improves the appearance of the loud speaker, 25 especially when the cord itself has an attractive appearance. The groove or recess between the peripheral portions 10 and 11 not only serves as a trough for the adhesive but also serves as a peripheral seat for the cord.

30 The type of joint described above is applicable to many different kinds of loud speakers regardless of whether the diaphragm 1 is conical in shape or flat, and regardless of whether the member 2 is a frustum of a cone, 35 a complete cone or any other member located at the rear of the diaphragm. For instance, it might be a sheet metal supporting member such as used in some types of radio loud speakers. Furthermore, the cord 12 need not 40 be an actual cord in the restricted sense of this term, but might be any filler which performs the same function as the cord. Moreover, the cone 1 need not be made of fibrous material as this part of the diaphragm struc- 45 ture, as well as the rear member 2, may be made of any suitable material which will permit the two parts to be joined together by a joint of the type herein disclosed.

The cord not only gives a finished and 50 pleasing appearance to the loud speaker, but also plays an important part mechanically in effecting an efficient and permanent joint between the two parts of the diaphragm structure. The use of a joint of the type herein 55 described greatly simplifies and cheapens the assembly of the diaphragm structure in the commercial manufacture of the loud speakers, because it is only necessary to rotate the two parts of the cone in unison, feed adhesive 60 to the peripheral groove and at the same time allow the cord to wind into the groove. The application of the cord to the groove may be readily accomplished by hand, by placing one end of the cord in the groove where it 65 will be held by the adhesive and then direct-

ing the cord in the groove as the two parts of the cone rotate, and as the cord tends to wind around the diaphragm structure, sufficient tension being applied to the cord to seat it firmly in the groove.

70

We claim:

1. A loud speaker comprising a conical diaphragm, a supporting member engaging the diaphragm around its peripheral portion, and a cord encircling the periphery of the 75 structure and located at the junction between the conical diaphragm and said supporting member, the supporting member and the conical diaphragm being cemented together at said junction and being cemented to said 80 cord.

2. A loud speaker comprising a conical diaphragm, a supporting member for the dia- 85 phram having a periphery corresponding in shape with the periphery of the diaphragm, the peripheral portion of the conical dia- phragm forming a recess with the peripheral portion of said supporting member, and a cord seated in said recess.

3. A loud speaker comprising a conical 90 diaphragm, a supporting member for the dia- phragm having a periphery corresponding in shape with the periphery of the dia- phragm, the peripheral portion of the conical dia- phragm forming a recess with the pe- 95 ripheral portion of said supporting member, a cord seated in said recess and a fillet of adhesive binding the cord, the supporting member and the conical diaphragm together.

4. A loud speaker comprising a conical 100 diaphragm, a supporting member cemented to the diaphragm around its peripheral portion, and a cord encircling the periphery of the structure and cemented to said support- 105 ing member and to the diaphragm, said cord concealing the joint between the supporting member and the diaphragm.

5. A loud speaker comprising a diaphragm structure including two members each of 110 which is at least a portion of a cone, said members being positioned with their bases together and being cemented together near their edges, and a cord encircling the pe- 115 riphery of the structure and cemented to said members, said cord concealing the joint be- 115

120 together the two members.

6. A loud speaker comprising a diaphragm structure including two members each of which is at least a portion of a cone, said members being positioned with their bases together and the peripheral portion of one of said members forming a recess with the peripheral portion of the other member, a cord located in said recess and a fillet of adhesive binding together the cord and said 125 members.

7. A loud speaker comprising a conical diaphragm and a cone frustum positioned with their bases together, the edge portions of the diaphragm and cone frustum flaring 130

134

- outwardly to form a peripheral recess between them, a cord in said recess and a fillet of adhesive binding together said cord, diaphragm and said cone frustum.
- 5 8. A loud speaker in accordance with claim 7 in which the diaphragm and cone frustum are made of fibrous material.
9. A loud speaker comprising a diaphragm structure including two fibrous members
- 10 each of which is at least a portion of a cone, said members being positioned with their bases together and being joined near their edges and each member having a peripheral portion flaring outwardly to form a recess
- 15 between them, and a cord located in said recess and encircling the periphery of the diaphragm structure.
10. A loud speaker comprising a diaphragm structure including two members
- 20 each of which is at least a portion of a cone, said members being positioned with their bases together and being joined near their edges and each member having a peripheral portion flaring outwardly to form a recess
- 25 between them, and a filler located in said recess concealing the joint between said members.
11. A. loud speaker comprising a diaphragm structure including two members
- 30 each of which is at least a portion of a cone, said members being positioned with their bases together and having outwardly flaring peripheral portions forming a recess between them, a filler in said recess, and a fillet of adhesive binding together said members and said filler.
12. A loud speaker comprising a diaphragm, a member located at the back of the diaphragm having a periphery corresponding in shape with that of the diaphragm, said diaphragm and member being joined near their edges and having outwardly flaring peripheral portions forming a recess between them, and a filler located in said recess concealing the joint between the diaphragm and said member.
13. A loud speaker comprising a diaphragm, a member located at the back of the diaphragm having a periphery corresponding in shape with that of the diaphragm, said diaphragm and member having outwardly flaring peripheral portions forming a recess between them, a filler located in said recess and a body of adhesive binding together the diaphragm, said member and the filler.
14. A loud speaker comprising a diaphragm, a member located at the back of the diaphragm having a periphery corresponding in shape with that of the diaphragm, and a cord cemented in place between the peripheral edge portions of the diaphragm and said member.

In testimony whereof we affix our signatures.
